STOCKING

Milton M. Meyers, Elkins Park, Pa., assignor to
Clarence L. Meyers & Co., Philadelphia, Pa.

Application July 31, 1936, Serial No. 93,553

8 Claims. (Cl. 66—173)

The present invention relates to knitted hosiery and more particularly to an improved construction for the welt fabric of a knitted silk stocking.

As known in the art, the welt of a knitted silk stocking is generally folded upon itself to provide a double ply of material and, in most instances, the yarn used in the welt is materially heavier than the yarn used in the leg fabric. Because of this double thickness of material and the heaviness of the yarn used, it will be understood that the welt fabric is less transparent than the leg portion of the stocking and, accordingly, the welt presents a surface which, in appearance, is considerably dull in comparison with the surface brightness of the leg portion of the stocking.

The difference in the surface brightness between the welt and leg portions of the stocking, when in use on the leg, is essentially noticeable after the stocking is dyed and finished. This is equally true whether silk or cheaper yarns, such as lisle or cotton, are used in knitting the welt, although, in the latter instance, the contrast in surface brightness between the welt and the leg portions is materially enhanced.

This invention, therefore, aims to overcome the apparent defect above mentioned by providing a stocking welt fabric of the type specified, the surface appearance of which will better harmonize with the surface appearance of the leg fabric, particularly when the yarn used to knit the welt is of a character and type different from the yarn used in knitting the leg portion, such as when the leg is knitted from silk yarn and the welt from cotton yarn.

According to the present invention, this desirable result is had by providing in the welt successive bands of courses, the adjacent bands having different surface reflections which, collectively, cooperate to destroy the apparent lack of brightness of the surface of the welt by imparting to the latter an increased lustre.

I have discovered that by incorporating in the welt, or at least in that portion thereof intended to constitute the exposed face of the fabric, a plurality of fabric bands of predetermined width, each band consisting of a multiplicity of courses, the yarn forming the courses of the alternating bands having a characteristic different from the yarn forming the courses of the interposed bands, the welt, due to the contrasting effect of the adjacent bands, acquires in appearance a surface brightness blending with that of the leg fabric and, accordingly, becomes devoid of the usual seemingly sharp differentiation in appearance.

between the welt and the leg portions of the finished stocking.

I have also found that particularly in stockings wherein the leg portion is knitted from silk yarn and the welt from cotton yarn, if two cotton yarns of the same color, but of slightly different shades, are used and each yarn is knitted to form a series of successive courses, there are formed distinct adjacent fabric bands which produce an optical effect destroying the striking contrast usually present between the welt and leg fabrics of stockings of the type mentioned.

The invention has the advantage of providing a distinctive arrangement of fabric bands of different characteristics, collectively producing a surface ornamentation which destroys the plainness of the usual plain knit welt fabric.

A characteristic feature of the invention resides in the fact that the alternation of bands of courses knitted from differently twisted yarns provides a stocking welt having an increased elasticity whereby the welt will snugly fit the thigh of the wearer and thus effectively maintain the stocking in position when worn.

The invention, therefore, has the advantage of producing a stocking welt possessing the required elasticity to properly engage the limb of the wearer without necessitating the incorporation of elastic in the knitted structure of the fabric, and yet having the needed stretchability to adequately fit the leg without causing discomfort or annoyance to the wearer.

Other important objects and advantages of the invention will be in part obvious and in part pointed out hereinafter.

In order that the invention and its mode of operation may be readily understood by those persons skilled in the art, I have, in the accompanying drawings, and in the detailed description based thereupon, set out possible embodiments of the invention. In these drawings:—

Figure 1 illustrates a knitted silk stocking wherein has been diagrammatically shown a welt embodying the preferred form of the invention.

Figure 2 is a view similar to Figure 1 diagrammatically representing a welt embodying a modified form of the invention.

Figure 3 is a diagrammatic illustration of one construction of the welt.

Figure 4 is a diagrammatic illustration of another construction of the welt.

Figure 5 is a diagrammatic representation of the method followed in knitting the preferred form of the invention shown in Figure 1.

Figure 6 is a diagrammatic representation of

the method followed in knitting the modified form of the invention shown in Figure 2.

Figure 7 diagrammatically illustrates a portion of a stocking similar to that shown in Figure 5 1 wherein the mode of knitting the welt is extended for a distance within the leg portion of the stocking to form the after-welt.

Having more particular reference to the drawings wherein like characters of reference will 10 designate corresponding parts throughout, I have shown a knitted stocking 1 comprising a leg and foot portion 2 and a welt 3.

The leg and foot portion 2 is constructed in the usual commonly known manner, that is, the 15 leg and foot portion 2 is made of ordinary plain knitted fabric.

The welt 3 is of the double ply construction and, in accordance with the present invention, is knitted to include series of fabric bands of 20 predetermined width, each band consisting of a multiplicity of courses, the respective series of bands being knitted from different yarns, that is, the courses within one series of bands are knitted from a yarn having a characteristic different from 25 the characteristic of a yarn forming the courses in the immediately adjacent bands.

With particular reference to the embodiment 30 of the invention shown in Figures 1 and 5, the fabric bands 5 constituted by the courses indicated by the reference character 7 in Figure 5 are formed from a "right" twist yarn 8, whereas the bands 6 constituted by the courses indicated by the reference character 9 are formed from a "left" twist yarn 10.

35 The formation of the respective series of bands from oppositely twisted yarns, as above mentioned, produces in the adjacent bands sets of wales of loops which are slanted in opposite directions. As shown, the wales of loops 11 in the bands 5 are inclined in one direction, whereas the wales of loops 12 in the bands 6 are inclined in the reverse direction. The relative inclination of the wales of loops 11 and 12 creates a distinctive surface effect in the adjacent bands 5 and 6, 40 each of which reflects the light rays at different angles, resulting in imparting to the entire fabric a surface effect which ornaments the welt in order that the same may harmonize more uniformly with the surface effect of the leg fabric.

45 In the modified form of the invention illustrated in Figures 2 and 6, the alternating series of bands 5a and 6a consist of a plurality of courses the courses of the adjacent bands being knitted from yarns having different degrees of twist and, as more clearly represented in Figure 6, the courses 13 of the bands 5a are knitted from a relatively low twist yarn 14, whereas the courses 15 in the bands 6a are knitted from a relatively high twist yarn 16. Thus, as in the preferred 50 form of the invention (Figures 1 and 5,) the modified form (Figures 2 and 6) includes distinctive adjacent fabric sections defined by the alternating series of bands 5a and 6a. Due to the fact that high twist yarn results in producing a 55 dull finish, and low twist yarn imparts a lustre to the dyed stocking, it will be appreciated that the alternating series of bands 5a and 6a of the courses 13 and 15, knitted from the respective yarns, cooperate to give to the welt surface a 60 brightness corresponding to that of the leg portion of the stocking.

In view of the foregoing, it will be understood 65 that because of the increased lustre or surface reflection imparted to the surface of the welt, any variation in the surface brightness of the welt

and leg fabrics is effectively overcome and, therefore, the differentiation in shade usually occasioned by such variation is practically eliminated. Likewise, it will be appreciated that since the adjacent bands 5 and 6 are respectively formed 5 of courses knitted from yarns having different characteristics, said bands produce a distinctive ornamental effect in the exposed surface of the welt as will clearly appear upon reference to the drawings.

10 By providing in the welt an alternating arrangement of fabric bands consisting of a plurality of courses, the courses in the adjacent bands being knitted from yarns of the same color but of slightly different shades there is likewise 15 produced a characteristic surface ornamentation which breaks the usual flat appearance of plain knitted welt fabric and produces a uniformity of appearance between the welt and leg fabrics.

In this connection, it will be understood that 20 in the manufacture of ingrain stockings, yarns of the same color, but of slightly different shades may be chosen whereas in the manufacture of dipped, dyed stockings, yarns adapted to dye off-shade with respect to one another may be selected 25 for the formation of the alternating arrangement of the fabric bands in the welt.

As hereinbefore stated, the welt 3 is of the 30 commonly known double ply type which is made by folding the fabric upon itself. In Figures 3 30 and 4, I have diagrammatically shown two types of welt in their unfolded formations.

Upon reference to Figure 3, it will be seen that 35 the welt includes an inner fabric 17 and an outer fabric 18, the two fabrics being separated by a course of transferred or picot stitches 19 which provide a line along which the welt is folded.

In the construction of this type of the invention, the outer fabric 18 embodies an alternating 40 arrangement of bands 5b and 6b, each consisting of a plurality of courses knitted from yarns of different characteristics in the manner above described. As to the inner fabric 17, it may be continuously knitted in the usual manner from a single yarn, as shown at 20.

As illustrated in Figure 4, the welt is also constructed to consist of an inner fabric 17' and an outer fabric 18' united by a course of transferred or picot stitches 19' forming the folding line of the welt. In practicing this form of the invention, both the inner and outer fabrics 17' and 18' respectively, are knitted from two yarns of different character to form an alternating arrangement of fabric bands 5c and 6c throughout the entire area of the welt. Due to the construction of the welt, as shown in Figure 4, the inner and outer fabrics 17' and 18' possess the same degree of elasticity and stretch.

In the type of stocking wherein it is desirable to provide an after-welt, I find it advantageous to 60 extend the alternating arrangement of bands beyond the welt and into the after-welt. An example of this latter construction is shown in Figure 7 of the drawings, from which it will clearly appear that the after-welt 22 is provided with 65 alternating distinctive adjacent bands 5d and 6d similar in character to the alternating adjacent bands 5' and 6' of the welt 3'. By proceeding in this manner, the welt fabric blends smoothly with the leg fabric and, accordingly, prevents an 70 abrupt demarcation between said fabrics.

As is diagrammatically shown by the alternating heavy lines and thin lines in Figures 1, 3, 4, and 7, the "left" twist yarn is twisted to a greater degree than that of the "right" twist yarn. How- 75

ever, it is to be understood that if found desirable or preferable, the "left" twist yarn may be twisted to a lesser degree than the "right" twist yarn.

5. In concluding, it is pointed out that the alternating arrangement of bands of courses knitted from yarns twisted at different degrees and in opposite directions, as hereinbefore specified, in addition to imparting a distinctive ornamental 10 surface to the welt, increases the elasticity of the latter so that the same properly engages the thigh of the wearer and effectively retains the stocking upon the leg.

This increased elasticity of the welt fabric is 15 had because of the difference of the character of the two yarns used in the knitting, that is, the different twists of the two yarns cooperate in such a manner that the loops of the courses formed by one yarn are acted upon by the loops 20 of the courses formed by the other yarn to relatively urge the respective loops to maintain their natural initial formation.

Manifestly the construction shown and described is capable of several modifications and, 25 accordingly, those modifications which come within the scope of the subjoined claims are considered within the spirit of the invention.

What I claim is:

1. In a knitted stocking, a knitted welt comprising an alternating arrangement of fabric bands of predetermined width, each band consisting of a multiplicity of successive courses, the courses of every other band being knitted from a 30 yarn twisted at a degree different from the degree of twist of the yarn forming the courses of the interposed bands, whereby the bands will have different degrees of surface brightness.

2. In a knitted stocking, a knitted welt comprising an alternating arrangement of fabric bands of predetermined width, each band consisting of a multiplicity of successive courses, the courses of every other band being knitted from a 35 yarn twisted in a direction opposite to, and at a degree different from the direction and degree of twist of the yarn forming the courses of the interposed bands.

3. In a knitted stocking, a knitted welt comprising an alternating arrangement of fabric bands of predetermined width, each band consisting of a multiplicity of successive courses, the courses of every other band being knitted from a "right" twist yarn, and the courses of the interposed bands being knitted from a "left" twist 40 yarn, the "left" twist yarn being twisted to a greater degree than that of the "right" twist yarn whereby the bands will have different light reflective characteristics.

4. In a knitted stocking, a knitted welt comprising an alternating arrangement of fabric bands of predetermined width, each band con-

sisting of a multiplicity of successive courses, the courses of every other band being knitted from a high twist yarn and the courses of the interposed bands being knitted from a low twist yarn whereby the bands will have different degrees of 5 surface brightness.

5. In a knitted stocking, a knitted double ply welt having an inner fabric and an outer fabric, the inner fabric consisting entirely of courses continuously knitted from a single yarn, the 10 outer fabric consisting of an alternating arrangement of fabric bands of predetermined width, each band consisting of a multiplicity of successive courses, the courses of every other band being knitted from a yarn having a twist different from 15 the twist of the yarn forming the courses of the interposed bands.

6. In a knitted stocking, a silk leg and foot portion consisting entirely of plain knit fabric 20 knitted from silk yarn having the same characteristics throughout, and a cotton knit welt portion, said welt portion comprising an alternating arrangement of fabric bands of predetermined width, each band consisting of a multiplicity of successive courses, the courses of every other 25 band being knitted from a cotton yarn having a twist different from the twist of the cotton yarn forming the courses of the interposed bands.

7. In a knitted stocking, the leg and foot portion, a welt, and an after-welt, said leg and foot portion consisting of plain knit fabric, and said 30 welt and after-welt consisting of an alternating arrangement of fabric bands of predetermined width, each band consisting of a multiplicity of successive courses, the courses of every other 35 band being knitted from a yarn having a twist different from the twist of the yarn forming the courses of the interposed bands.

8. In a knitted stocking, a leg and foot portion, a double ply welt, and a single ply after-welt: 40 said leg and foot portion consisting of plain knit fabric; said double ply welt having an inner fabric and an outer fabric, the inner fabric consisting entirely of courses knitted from a single 45 yarn, the outer fabric consisting of an alternating arrangement of fabric bands of predetermined width, each band consisting of a multiplicity of successive courses, the courses of every other band being knitted from a yarn having a degree of twist different from the degree of twist 50 of yarn forming the courses of the interposed bands; and said after-welt consisting entirely of an alternating arrangement of fabric bands of predetermined width, each band consisting of a multiplicity of successive courses, the courses of every other 55 band in said after-welt also being knitted from yarn having a degree of twist different from the degree of twist of the yarn forming the courses of the interposed bands.

MILTON M. MEYERS. 60
